RICHARD B. SMITH, OF SYDNEY, NEW SOUTH WALES, AUSTRALIA.

MULTIPLE-RECORD PHONOGRAPH.

1,023,047.

Specification of Letters Patent.

Patented Apr. 9, 1912.

Application filed February 8, 1906. Serial No. 300,027.

To all whom it may concern:

Be it known that I, RICHARD BARTHOLOMEW SMITH, a subject of the King of Great Britain, residing at Sydney, New South Wales, Australia, have invented certain new and useful Improvements in Multiple-Record Phonographs, of which the following is a specification.

My invention relates to phonographs wherein I employ means for carrying a plurality of records, say four, six or more, each of which is adapted to be brought into cooperative relation to a reproducer in such manner that the record will remain in place and be rotated axially while the reproducer travels along said record, after which the next record is brought into position with relation to the reproducer, so that the aforesaid operations may be repeated, and so on throughout the number of records used in the machine.

The machine embodies a carrier for the desired number of records, means for holding the carrier at rest, means for rotating one record while the carrier is at rest, a reproducer, and means for imparting traversing motion to the producer.

One feature of novelty of the new machine consists in an automatic feed mechanism for the record carrier. This mechanism includes a shaft geared to the record-carrier, a sliding member, a pawl and ratchet device actuated by the sliding member for operating the aforesaid shaft, and means for moving the sliding member. In connection with the shaft and the record carrier I have provided a locking mechanism which holds the carrier at rest, but which is releasable automatically at the period of moving the carrier, so as to present a new record to the reproducer.

Another feature of my apparatus is a means for returning the reproducer automatically to its starting position after said reproducer shall have traversed one of the records. In addition to the common feed screw, my machine is equipped with a coarse thread feed screw which is suitably driven, and the traveler is equipped with two nuts or nut sections which are adapted to respectively engage with the feed and return screws. A shiftable tension arm is as-

sociated with the traveler so as to hold it in one position or the other, in order that the feed nut or the return nut may have engagement properly with the feed screw or the return screw, according as one or the other is in operation. Combined with this tension arm are tripping devices, one on the feed screw and the other on the return screw, said devices being so related to the arm as to automatically shift the same when the traveler reaches the limit of its motion in one direction or the other.

Various other features of my machine will be hereinafter described and defined by the claims.

Reference is to be had to the accompanying drawings, forming a part of this specification, wherein like characters of reference are used to indicate corresponding parts in the several figures of the drawings.

Figure 1 is an elevation looking at the rear of a multiple record phonograph, constructed in accordance with my invention; Fig. 2 is an end elevation looking at the right hand end of the machine shown by Fig. 1; Fig. 3 is a plan view of the invention, parts being broken away and in section, in order to more clearly represent other parts; and Fig. 4 is an elevation looking at the front side of the machine; Fig. 5 is a plan view of a part of the machine illustrating automatic stop devices by which the record carrier may be arrested at the end of the reproduction on each record or at every record or third record; Fig. 6 is an elevation looking at one end of the devices shown by Fig. 5, and Fig. 7 is a view looking at the other end of Fig. 5.

A designates a suitable base, herein shown in the form of a casting adapted to inclose the motor or driving mechanism for the operation of the several parts of the machine. I have not considered it necessary to show in detail the motor, but in Fig. 2, the driving pulley is indicated by dotted lines at a. On the base A are the posts b, having suitable bearings for the shaft B of a record carrier. This carrier is shown by the drawings in the form of a skeleton reel, which is constructed to accommodate a desired number of mandrels for the appropriate number of record cylinders, said record car-

rier being adapted to rotate on a horizontal axis, although the carrier normally remains at rest or in a locked position, while the reproducer is operated to have traveling motion with respect to one of the records in said carrier. The carrier is shown as having a spider c at one end, said spider being provided with a plurality of bearings c' . At the other end of the carrier is a hub c^2 , which is equipped with a plurality of arms c^3 , the latter corresponding in number to the radial members of the spider c , and being provided with appropriate bearings c^4 , which are in alinement with the bearings c' of the spider c . The arms c^3 , however, are pivoted to the hub c^2 , in order that each arm and the bearing c^4 may be adjusted to the position indicated by dotted lines in Fig. 3, thus throwing the arms c^3 out of register 20 with a record cylinder on one of the mandrels for the purpose of removing and interchanging the record cylinders on said carrier. The hub c^2 and the pivoted arms c^3 constitute another spider, the members of which are adjustable, whereas the members of the spider c are non-adjustable. The pivoted arms c^3 are held in their working positions by the spring members or fingers d of a plate spring D , which is fastened to the carrier shaft B , or to the hub c^2 , said members or fingers d being arranged to act against the pivoted ends of the arms c^3 , for the purpose of holding them in their radial working positions. The spider c is 35 equipped with a number of brackets e , which are fastened thereto on the outer side of the record carrier, as shown by the several figures of the drawings, and each bracket is equipped with a bearing e' , which is in alinement with one of the bearings c' of the spider c .

A plurality of arbors E are journaled in the bearings c' and e' of the carrier spider c , one end of each arbor being pointed so as 45 to engage one bearing, e' . Each arbor has its other end pointed to be journaled in one bearing c^4 , on a pivoted arm c^3 of the other spider, whereby each arbor E is mounted to rotate freely in the bearings of the respective spiders, and at the same time said arbor is so mounted in the spider c and one of its brackets e , that it will be properly supported when the arm c^3 is adjusted away from the unsupported end of the arbor, for 55 the purpose of interchanging the records of the mandrel of the arbor. It will be understood that each arbor E is equipped with a mandrel E' , on which is adapted to be placed a cylindrical record, the latter being 60 indicated at F . It will be understood, furthermore, that the mandrel E' and the record F , are adapted to rotate with the arbor E ; and for the purpose of driving the arbor E when the record thereon is presented to

a reproducer, I have provided the following mechanism: A post g is erected on the base A , and is provided with a shaft bearing g' , see Fig. 4. In this bearing is a short shaft G , on one end of which is secured a spur gear pinion g^2 . Each arbor E is provided between the spider c and the bracket e with a pinion h , and when the carrier is rotated one step so as to bring a fresh record into coöperative relation to a reproducer, the pinion h on the arbor of the record which is thus presented is adapted to mesh with the pinion g^2 on the shaft G , whereby the arbor and the record are adapted to rotate on their axes. The shaft G is extended at one end beyond the bearing g' , which is 75 in alinement with the driving pulley a , and these two pulleys a , a' , are connected operatively by an endless driving belt a^2 , as indicated by full and dotted lines in Fig. 2, whereby the shaft G is driven automatically 80 from the motor.

Near the front side of the machine is a horizontal track rail i , and in suitable posts i' near the rear side of the machine is a track rod I , the latter being parallel to the rail i . On the track rod I is a traveler J , and from this traveler extends an arched or bowed reproducer carrier K , the latter being rigid with the traveler J , and extending over the record carrier, so that the free end of the reproducer carrier may have engagement with the rail i , for the purpose of resting thereon during the period that the carrier K is operated to impart the traversing movement to a reproducer L in contact 95 with one of the cylinder records in the record carrier. The reproducer L may be of the usual or any preferred form, and it is shown as being mounted centrally on the arched carrier K , so as to have engagement with the uppermost record in the record carrier. The arched carrier K is represented by Fig. 2 as having a notched free end k , adapted for engagement with the rail i , and in this notched end is fitted a bolt k' , 100 which is adapted to be moved inward so as to rest on the rail for the purpose of lifting the record carrier so as to maintain the reproducer above the record and prevent it from engaging therewith during the operation of removing and replacing the records.

My machine is equipped with two screw shafts or spindles, the same being located on the rear side of the machine, and being disposed in horizontal parallel positions, one 110 above the other. For the purpose of distinguishing the two screw spindles, I will designate one of them as the feed screw M , while the other will be designated as the return screw N . The feed screw M is provided with a continuous fine screw thread, while the return screw has quite a coarse 115 thread running in an opposite direction to

the fine thread of the screw M. The two screws are journaled in appropriate bearings of the post m, which are erected on the base A, and said screws are driven from the shaft 5 G by the following means: In addition to the gear pinion g², and the pulley a', the shaft G is provided with a gear m', which meshes with an idle gear m², that is mounted on a shaft m³ in the post m⁴, as indicated 10 by full and dotted lines in Fig. 2. This gear m² in turn meshes with a gear n on the screw M. It will be seen that the gear m' of the shaft G drives the gear m², which in turn drives the gear n of the feed screw M, 15 and this gear n in turn drives the gear n' of the return screw N.

The traveler J is provided with two arms, O, P, the former extending in an inclined direction below the feed screw M, while the latter extends from the reproducer carrier in a horizontal direction, so as to lie over the return screw N. The arm O is provided 20 at its free end with a feed nut o, adapted to have engagement with the feed screw M, 25 whereby the required motion will be given by the feed screw to the traveler for moving it in one direction along the slide rod I. The arm P has a return nut p, which is adapted to mesh with the threads of the return screw N, but the arms O, P, are so related to the traveler and to the two screws that only one of the arms will be presented 30 in position for the nut thereon to engage with one of the screws, the nuts o and p being adapted for engagement alternately with the feed and return screws, respectively.

I have equipped my machine with means for automatically reversing the position of 40 the traveler J, as it approaches the limit of its movement in either direction, so as to shift the feed nut out of engagement with the feed screw and simultaneously place the return nut into engagement with the return screw, and vice versa. Loosely mounted on the traveler J at one end thereof is a short collar Q, said collar being provided with a slot q, in which is adapted to play a stud or pin q', the latter being fast with the traveler J, as shown by Fig. 3. The collar Q is shown as having an upstanding arm Q', on which is affixed the weight Q², and this collar with its weight is adapted to be shifted for a limited distance within the length of 55 the slot q, in order that the weight may be placed to one side or the other of the vertical plane of the traveler, for the purpose of holding said traveler in the required position to maintain the feed nut in engagement 60 with the feed screw or the return nut in engagement with the return screw. The collar Q is, furthermore, provided with an arm R, which extends alongside of the feed screw M, and is provided with an upstanding fin-

ger r, the latter being disposed in the path 65 of a trip R' on the return screw N. The feed screw M is also provided with a trip R², which is adapted for engagement with the finger r, and as the traveler moves in one direction or the other, the finger is brought 70 into engagement with one trip or the other on the screws, so as to reverse the position of the weighted collar, and thereby shift the traveler so that the nuts will be moved, the one into engagement with one screw and the 75 other out of engagement with the other screw.

When the feed screw M operates to impart movement to the traveler J, the carrier K and the reproducer L, so as to make said reproducer traverse the cylindrical record which is properly presented thereto by the record carrier, the feed nut o on the arm O is held in engagement with said feed screw M by the weight Q² on the stem or arm Q', 80 and at the same time the free end of the reproducer carrier K rests on the track rail i, while the nut p is lifted from engagement with the reverse screw N. As the traveler J reaches the limit of this movement toward 90 the left in Fig. 3, a part of the trip R² engages with the arm O, so as to depress the latter for the purpose of releasing the feed nut o from engagement with the screw M, thus arresting the motion of the traveler J 95 in one direction. This operation turns or rocks the traveler on the slide rod I, and the stud q' thereof operates on the collar Q, so as to shift or turn the position of said collar and of the weighted arm Q', thereby moving 100 the carrier K and the arm P, so that the free end of said carrier will not engage with the rail i, while the return nut p will be depressed into engagement with the thread of the return screw N. As said return screw is 105 driven from the feed screw M, it follows that the nut p will be operated to move the traveler in the opposite direction so as to return the carrier K, and the reproducer L, back to the starting point. The return 110 movement of the parts will be at a faster speed than the feed motion given thereto by the screw M, because the return screw N has a coarse thread of quick pitch, but as the traveler reaches the limit of its movement toward the right of Fig. 3, the trip R' will engage with the finger r, on the arm R in a 115 way to again rock or turn the carrier J, and thereby disengage the return nut p from the return screw N, and simultaneously move the feed nut o into engagement with the feed screw M, as will be readily understood.

The means for automatically turning the record carrier one step at a time, operates in unison with the traveler J, as I will now proceed to describe. The shaft B of the record carrier is provided with a bevel gear s, having meshing engagement with another

bevel gear s' on a horizontal shaft S , the latter being journaled in appropriate bearings, and extending, substantially, at right angles to the shaft B . At its rear end this 5 shaft S is provided with a ratchet t , with which engages a feed pawl t' , the latter being pivoted to a feed slide T , supported in a horizontal position by suitable posts t^2 . One post is provided with a check pawl t^3 , 10 which is adapted for engagement with the ratchet t , so as to hold the shaft S against rotation in its bearings, except when operated upon by the pawl t' . The slide T is normally impelled in one direction by a 15 suitable refractor, such as the spring T' . The slide T is disposed in the path of an arm T^2 , which projects rearwardly from the traveler J , as shown by Figs. 1 and 3, and as the traveler is returned by the action of 20 the screw N on the nut p , this projection or arm T^2 engages with the slide T , so as to move the pawl t' toward the right in Fig. 1. This operation turns the ratchet t a distance equivalent to one tooth thereof, and 25 the shaft S is thus given a partial turn for the purpose of rotating the shaft B and the record carrier, so that a fresh record on one of the mandrels E' is brought into position below the reproducer L . I, also, provide 30 means for locking the record carrier against movement, except when acted upon by the pawl and ratchet feed mechanism, which is moved at intervals by the arm T of the traveler J . In one form of my invention 35 the locking mechanism consists of a disk U , which is fixed to the shaft B , said disk being provided with suitable openings indicated by dotted lines in Fig. 3. A spring arm U' is provided with a stud adapted to enter one 40 of the openings of the disk U , and this arm is provided with a projection u , which is adapted to engage with a tooth of a star wheel w' , that is fixed to the shaft S . The tension of the arm U' normally impels the 45 stud into one of the holes of the disk U , for the purpose of locking the shaft B of the record carrier against axial rotation, but when the shaft S is operated by the pawl and ratchet, as described, a tooth of the 50 star wheel w' pulls on the projection u and the arm U' , so as to withdraw the stud from the disk U , thus permitting the shaft S to turn the shaft B of the record carrier, as heretofore described.

55 The arm T^2 is shown as being divided and the outer part thereof is pivoted to the inner part, thus providing a jointed arm. When it is desired to make the reproducer travel a second time over the same record and 60 thereby repeat the reproduction of the musical or talking number, the operator should turn backward the outer part of this jointed arm, thus preventing the arm T^2 from operating the slide bar T of the mechanism.

for automatically feeding the revoluble record carrier. 65

My machine is also equipped with a stop motion by which the operation of the reproducer may be arrested automatically at the end of the reproduction from each record, and also with a stop motion adapted for adjustment so as to automatically present every second, third or fourth record of the record carrier to a working position relative to the reproducer. 75

The stop device for arresting the machine at the end of the reproduction from each record is operated by the return of the reproducer carrier K to normal position. One member v of the motor or driving mechanism has a stud v' , see Fig. 6, and with this stud co-operates a stop lever V , hung on a bracket v^2 within the casing A . To this lever is pivoted a link W , the upper end of which is pivoted to one arm of a lever X , fulcrumed on a fixed post z . The other end of the lever X has pivoted thereto a jointed arm Y , the member y of which is in the path of the reproducer carrier K . As this carrier is returned to its starting position, after completing its travel along the record, the end k of the carrier rides on the arm Y , so as to move the latter and thereby actuate the lever X so as to move the lever V through the link W , whereby the operation of the motor is arrested. Should it be desired to allow the machine to continue in operation, the pivoted member y of the arm Y is turned around so as to move it out of the path of the record carrier K . 95 100

In addition to the described stop motion, I also provide stop devices by which every second, third or fourth record may be used. A rock shaft Z is journaled in bearings on posts, and at its ends this shaft has arms Z' , Z^2 . The arm Z^2 is connected by a pin z with the lever X for operating the latter when the shaft is rocked. Each arm c^3 of the spider for the record carrier is provided with a pivoted finger z' , which is adapted to be turned to a position at right angles to the arm, as shown by full lines in Figs. 5 and 7, or to be turned to a position in line with the arm as indicated by dotted lines in Fig. 5. The arm Z' is adapted to lie in the path of the fingers z' when they lie at right angles to the arms c^3 for the purpose of operating the arm Z' , the rock shaft Z , the arm Z^2 , and the levers X and V to stop the motor. It is evident that the second, third, or fourth fingers z' may be adjusted out of position so as to clear the arm Z' and thus permit the other fingers to engage with said arm for operating the stop motion at the required intervals. 110 115 120 125

Changes in the form, size, proportion, and minor details in construction may be made without departing from the spirit of the in-

vention or sacrificing any of the advantages thereof, and I, therefore, reserve the right to make such alterations and modifications as fairly fall within the scope of my invention.

Having thus described my invention, what I claim as new and desire to secure by Letters Patent is:—

1. In an apparatus of the class described, 10 a record carrier, a traveler for a reproducer, a shaft geared to the record carrier, a slide- 15 able member in the path of the traveler, a pawl carried by the slide, and a ratchet mounted on the shaft and coöperating with 20 said pawl.

2. In an apparatus of the class described, 25 a record carrier, a traveler for a reproducer, a shaft geared to the record carrier, means actuated by the traveler for rotating the 30 shaft with a step by step motion, and means controllable by the shaft for locking the record carrier in the intervals of the feed given thereto by the shaft.

3. In an apparatus of the class described, 35 feed and return screws, a slide rod, a repro- ducer traveler mounted to slide and turn on the rod and provided with arms, nuts carried by the arms for alternately engaging the 40 screws, a collar on one end of the traveler and having limited turning movement in- dependent of the traveler, said collar being provided with a weighted arm and with a 45 finger, and a trip on each feed screw and adapted to engage the finger of the collar.

4. In an apparatus of the class described, 50 feed and return screws, a slide rod, a repro- ducer traveler mounted to slide and turn on the rod and provided with arms, said trav- 55 eler having a recess in one end, nuts carried by the arms for alternately engaging the screws, a collar loosely mounted on the trav- 60 eler and having a stud working in the recess of the traveler, said collar being provided with a weighted arm and an arm carrying a 65 finger, and a trip on each of the screws and adapted to engage the said finger.

5. In a machine of the class described, a 70 record carrier provided with operating arms, means for operating the carrier, and 75 means controllable by said arms for arrest- 80 ing the operating means.

6. In a machine of the class described, a 85 record carrier provided with operating arms, means for operating the carrier, and 90 means controllable by said arms for arrest- 95 ing the operating means, said operating arms being adjustable individually into and 100 out of working position.

7. In a machine of the class described, 105 a record carrier, means for operating the same, a reproducer carrier, a locking lever for arresting said operating means, another 110 lever, a jointed arm connected with the last 115 mentioned lever and adjustable relative to

the reproducer carrier, a rock shaft for op- 120 erating the second lever, and means operated by the record carrier for rocking the shaft.

8. In an apparatus of the class described, 125 a shaft, a reel mounted thereon and carrying a plurality of revoluble record supporting 130 arbors, means for operating the shaft, an apertured disk on the shaft; a spring arm having a pin engaging the apertured disk, and a star wheel carried by the shaft oper- 135 ating means and engaging the spring arm to disengage it from the said disk.

9. In an apparatus of the class described, 140 a motor having a stud on a movable mem- 145 ber thereof, a multiple record carrier, a traveler, a reproducer carrier carried by the traveler, means for operating the traveler, an arm projecting into the path of the re- 150 producer carrier, a pivoted stop lever adapt- 155 ed to be moved into the path of the stud of the movable member of the motor, and a 160 connection between the pivoted stop lever and arm whereby the former will be op- 165 erated by the latter.

10. In an apparatus of the class described, 170 a record carrier, a motor, a traveler, a re- 175 producer carrier carried by the traveler, means for operating the traveler, a pivoted arm projecting into the path of the repro- 180 ducer carrier, a pivoted member adapted to be moved into the path of a movable mem- 185 ber of the motor, means for operating said member from the arm, a shaft, a connection between the shaft and pivoted arm, and 190 means for operating the shaft from the record carrier.

11. In an apparatus of the class described, 195 a multiple record carrier, a reproducer car- 200 rier, means for operating the said carrier, a spring pressed slide, means for operating the multiple record carrier from the slide, 205 and means for operating the slide from the reproducer carrier.

12. In an apparatus of the class described, 210 a shaft, a plurality of revoluble record sup- 215 porting arbors on the shaft, means for op- 220 erating the shaft, a member carried by the shaft, a spring arm having interlocking engagement with the member, and a mem- 225 ber carried by the shaft operating means for disengaging the spring arm from the first 230 named member.

13. In an apparatus of the class described, 235 a multiple record carrier, a reproducer car- 240 rier, means for operating the reproducer carrier, a spring pressed member, means for 245 operating the multiple record carrier from the said member, and means for operating the member from the reproducer carrier.

14. In an apparatus of the class described, 250 a multiple record carrier, means for operat- 255 ing the said carrier to bring the records in proper position, a rocking reproducer car- 260 rier, means for rocking said carrier, a feed

device for said carrier, controlled by the
rocking movement thereof, means controlled
by the reproducer carrier for stopping the
apparatus at the end of the reproduction of
5 each record, and means controlled by the
record carrier for stopping the apparatus to
permit of bringing any one of the records
into working position.

In testimony whereof I have signed my
name to this specification in the presence of 10
two subscribing witnesses.

RICHARD B. SMITH.
